UNITED STATES PATENT OFFICE.

WALTER E. OTWELL, OF LINN, KANSAS.

DESIGN FOR A RADIATOR-CAP ORNAMENT.

Application filed September 20, 1928. Serial No. 28,221. Term of patent 7 years.

To all whom it may concern:

Be it known that I, WALTER E. OTWELL, a citizen of the United States, residing at Linn, in the county of Washington and State of Kansas, have invented a new, original, and ornamental Design for Radiator-Cap Ornaments, of which the following is a specification, reference being had to the accompanying drawing, forming part thereof.

The figure is a perspective view of a radiator cap ornament, showing my new design.

I claim:

The ornamental design for a radiator cap ornament as shown.

WALTER E. OTWELL.
